[57] CLAIM

The ornamental design for an oilstove, substantially as shown.

DESCRIPTION

FIG. 1 is a front, top perspective view of an oilstove showing our new design;
FIG. 2 is a front elevational view thereof;
FIG. 3 is a top plan view thereof;
FIG. 4 is a right side elevational view thereof;
FIG. 5 is a left side elevational view thereof;
FIG. 6 is a rear elevational view thereof;
FIG. 7 is a bottom plan view thereof;
FIG. 8 is a front, top perspective view of a modified embodiment of the oilstove shown in FIG. 1;
FIG. 9 is a front elevational view thereof;
FIG. 10 is a top plan view thereof;
FIG. 11 is a right side elevational view thereof;
FIG. 12 is a left side elevational view thereof;
FIG. 13 is a rear elevational view thereof; and
FIG. 14 is a bottom plan view thereof.
